UNITED STATES PATENT OFFICE.

JULES HUMBRECHT, OF FRIEDENAU, NEAR BERLIN, GERMANY, ASSIGNOR TO THE FIRM OF OPTISCHE ANSTALT C. P. GOERZ AKTIENGESELLSCHAFT, OF FRIEDENAU, GERMANY.

PERISCOPE WITH A TRANSPARENT HOOD.

Application filed August 23, 1921. Serial No. 494,498.

(GRANTED UNDER THE PROVISIONS OF THE ACT OF MARCH 3, 1921, 41 STAT. L., 1313.)

To all whom it may concern:

Be it known that I, JULES HUMBRECHT, a citizen of the German Republic, and resident of Friedenau, near Berlin, Germany, have invented certain new and useful Improvements in and Relating to Periscopes with Transparent Hoods (for which I have filed applications for patent in Germany December 21, 1915; Hungary June 4, 1917, 10 and Austria December 13, 1917), of which the following is a specification.

This invention relates to a periscope particularly for submarines provided with a light entrance reflector adapted to rotate 15 about an axis substantially transverse to the longitudinal main casing of the instrument so as to allow observation of objects under variable elevation such as air-crafts. The invention relates more particularly to 20 such instruments of this kind which are provided with a transparent hood for closing the instrument casing at the light entrance end and with a lens movable with the entrance reflector for compensating the 25 light ray distorting the effect of the transparent hood of the instrument.

The invention consists in an improved instrument of the kind referred to allowing convenient observation of objects of 30 varying elevation, wherein for securing this effect a coupling between the rotatable entrance reflector and the correcting lens movable therewith is provided of such kind that the correcting lens is rotated with 35 double the angular velocity of the entrance reflector. Such kind of coupling between the entrance reflector and the correcting lens has the effect that the parts are permanently in operative position with relation to each 40 other irrespective the elevation under which the observation takes place.

An embodiment of the invention is illustrated on the annexed drawing and described in the following specification with 45 reference to the drawing.

Fig. 1 shows the instrument in axial section partly in side elevation.

Fig. 2 is an axial section through the upper part of the instrument showing the 50 rotatable entrance reflector and the correcting lens in a position different from that shown in Fig. 1.

The transparent hood of the instrument

at the light entrance end is designated 1. Centrally to this globular hood is arranged 55 the light entrance reflector which in the embodiment illustrated on the drawing consists of two right angled triangular prisms 2, 3 which are cemented together. The contact surface 4 of the prisms has the function of a surface reflecting on both its sides. In front of the entrance reflector 4 is arranged as already proposed a correcting lens 5 which compensates the lens effect of the globular hood 1. The correcting lens 5 is 60 coupled with the entrance reflector 4. For this purpose the reflector 4 is connected with a toothed wheel 6 and the correcting lens 5 with a toothed wheel 7, the said two wheels meshing with toothed racks 8 and 9 respectively, said toothed racks being provided on a common carrier 10 connected to a rod 11 which is adapted to be moved by the observer.

12 designates the objective system; 13 is 75 a transparent plate arranged in the image plane of the objective and provided with suitable marks, 14 and 15 designate the two elements of an image reversing system and 16 an angular ocular.

The path of a pencil of rays indicated in the drawings shows that a special construction of the rotatable reflector with which the instrument is provided affords the possibility that even in the zenith position of 85 the reflector shown in Fig. 2 light rays are reflected from the double sided reflector 4 so as to impinge on the objective 12 and to form an image of the object in zenith position viewed at by the instrument.

What I claim is:

1. In a periscope with a transparent hood closing the light entrance end of the instrument in combination an entrance reflector and a lens in front of the entrance reflector adapted to compensate the lens effect of the hood both rotatable about a common axis substantially at right angles to the axis of the periscope, gearing adapted to simultaneously rotate said lens and said entrance reflector the angular velocity communicated by said gearing to said lens being double the velocity communicated to said entrance reflector.
2. In a periscope with a transparent hood 105 closing the light entrance end of the in-

strument in combination an entrance reflector and a lens in front of the entrance reflector adapted to compensate the lens effect of the hood both rotatable about a common 5 axis substantially at right angles to the axis of the periscope, gearing adapted to simultaneously rotate said lens and said entrance reflector the latter being formed of a compound prism having two symmetric 10 halves with one adjacent reflector surface forming a double sided operative entrance reflector for the instrument said compound prism having an angular velocity communicated to it by said gearing half that of said 15 lens.

3. In a periscope with a transparent hood closing the light entrance end of the instrument in combination a compound prism of square cross section consisting of two right 20 angled triangular prisms with cemented

hypotenuse surfaces and a lens in front of said compound prism adapted to compensate the lens effect of the hood said compound prism and said lens rotatable about a common axis substantially at right 25 angles to the axis of the instrument, said axis of rotation lying within the cement layer of the compound prism, gearing adapted to simultaneously rotate said lens and said compound prism the angular 30 velocity communicated by said gearing to said lens being double the velocity communicated to said compound prism.

In testimony whereof I have signed this specification in the presence of two sub- 35 scribing witnesses.

JULES HUMBRECHT.
